UNITED STATES PATENT OFFICE.

CHARLES RUPP, OF PHILADELPHIA, PENNSYLVANIA, ASSIGNOR TO J. S. THORNE COMPANY, OF PHILADELPHIA, PENNSYLVANIA, A CORPORATION OF PENNSYLVANIA.

AUTOMATIC RELEASING DEVICE FOR WINDOW-SASHES.

SPECIFICATION forming part of Letters Patent No. 709,800, dated September 23, 1902.

Application filed June 7, 1902. Serial No. 110,687. (No model.)

To all whom it may concern:

Be it known that I, CHARLES RUPP, a citizen of the United States, residing in Philadelphia, Pennsylvania, have invented certain 5 Improvements in Automatic Releasing Devices for Window-Sashes, of which the following is a specification.

My invention consists of certain improvements in fireproof window-sashes, and more 10 particularly of an improved attachment for such sashes, the invention having for its object the provision of a device which shall automatically operate to release a raised window-sash and permit it to close when a pre-determined rise of temperature occurs in its 15 immediate vicinity. This object I attain as hereinafter set forth, reference being had to the accompanying drawings, in which—

Figure 1 is a front elevation, partly in section, of a window-sash equipped with my improved device. Fig. 2 is a sectional elevation of a portion of one of the side members of the sash, showing the method by which the flexible connection between the sash and the 20 counterweight is attached to the sash. Fig. 25 3 is an inverted plan view taken through the lower member of the sash directly under one of the side members, and Figs. 4 and 5 illustrate other methods of attaching the counterweight connection to the sash. Fig. 6 is a 30 detailed view of a modification.

In connection with the equipment of buildings with fireproof window-sashes, frames, and other similar parts it has been found advisable to also provide means or mechanism 35 by which such fireproof sashes will be permitted to automatically close if in an open position in case of the breaking out of a fire, with a consequent rise of temperature, in their immediate vicinity.

The form of device shown in the above drawings is particularly adapted for application to the lower of the two sashes usually found in windows and has been devised with 40 the idea of providing a device which shall certainly operate when there has been but a very small rise of temperature above what has been found to be the danger limit.

In the above drawings, A is a metallic win-

dow-frame of any desired construction, in 50 which are upper and lower sashes B and B'. The sashes consist of hollow metallic frameworks, as indicated in the figures, and the lower sash is shown as provided with counterweights a, having chains a² passing over 55 pulleys a', carried by the frame A. From Fig. 2 it will be seen that the lower frame is provided with channel-shaped sections b within the upper portion of its hollow side members, there being similar pieces b', suitably 60 held within the hollow of its lower member b², directly under its side members b³. Passing through suitable openings in these sections b and b' is a member C, shown in the drawings as consisting of a heavy wire or rod, 65 although it will be understood that, if desired, it may be a metallic cable or chain. This member has an eye or hook c at one end, to which is attached the chain or cable a², connected to the counterweight a, and has on 70 its lower end a body of material c', preferably composed of a metal having a relatively low fusing-point. The end of the member C is preferably roughened or nicked, so as to retain the body c' in position, this latter being 75 cast around said end and bearing against the under surface of the channel-section. If desired, this body of fusible material c' may be cast into the hollow of an iron nut c², Fig. 4, in which the nicked end of the member C 80 has been previously placed, thus giving a greater bearing-surface upon the section b' and also having a greater resistance to a pulling strain exerted upon the member C. Another method of attaching the fusible piece 85 c' is shown in Fig. 5, in which the end c³ of the member C is made tapering upwardly, the opening through the section b' being large enough to permit of the passage of this end. The body of fusible material has a tapered 90 opening through it which fits the end of the member C, as shown, retaining it in position until it is released by the fusing of the material. The inverted plan view of one corner of the window-sash illustrated in Fig. 2 clearly 95 shows the position which the beveled section b' occupies relatively to the side member of the sash, also showing the notch or groove a³.

for the accommodation of the glass and its retaining material.

In use a sash having my improved device ordinarily operates in the well-known manner, although should the sash be in a raised position when flames or heated gas from a fire pass through the window between the lower member b^2 of the sash and the sill b^4 such heat would fuse the bodies of fusible material c' , thus releasing the members C and allowing the sash B to drop to its closed position under the influence of gravity, rendering it for the time being entirely independent of the counterweights a. If desired, the end of the member C may be threaded and the body of fusible material c' be screwed thereon instead of being cast in position.

The advantage of my improved construction over those at present known in the art will be understood when it is noted that the fusible material for releasing the sash from its counterweights is placed in a position where it will be exposed to flame or heated gas as soon as the flame or heated gas attempts to pass into or out of the window, being thereby quickly acted upon to permit the closing of the sash. This is an extremely important feature, since unless all windows be closed at an early stage of a fire or before it attains a great headway such devices are utterly useless.

I claim as my invention—

1. The combination of a window-sash, a counterweight having means for operatively connecting it to said sash, said means being detachably held to the sash at a point adjacent to its lower edge, substantially as described.

2. The combination of a window - sash, a counterweight and a connection between said two members, the same having means attaching it to the sash at a point adjacent to the lower edge thereof, and being constructed to automatically operate to disconnect said sash from its counterweight upon a predetermined rise of pressure, substantially as described.

3. The combination of a window - sash, a counterweight and a connection between said two members, with a device normally attaching said connection to the lower portion of said sash and including fusible material whereby the sash is disconnected from the counterweight when said device is exposed to a predetermined rise of temperature, substantially as described.

4. The combination of a window - sash, a counterweight therefor, a connection between said two members, a portion of said connection extending to the lower part of the sash, a body of material upon the connection whereby the latter is attached to said sash, said material having a relatively low fusing-point, substantially as described. 60

5. The combination of a sash, a counterweight therefor, a connection extending between said two members, said connection passing through a side member of the sash to the lower portion thereof, with a body of the material of relatively low fusing-point holding the connection to the sash, substantially as 70 described.

6. The combination of a window - sash, a counterweight therefor, a chain extending between said two members, a portion of the chain passing through the side member of the 75 sash to the lower edge thereof and having a body of material of relatively low fusing-point normally holding it to the sash, substantially as described.

7. The combination of a window - sash, a counterweight therefor, a chain connecting said two members, said chain passing through one of the side members of the sash, and being held to the sash by a body of material of 80 relatively low fusing-point having a body of relatively infusible material substantially surrounding it, substantially as described.

8. The combination of a frame, a window-sash mounted therein, rods extending through the side members of the sash, counterbalancing devices attached to the upper ends of said rods and a fusible head attached to the lower end of the rods and bearing against the under side of the sash, substantially as described. 90

9. The combination of a frame, a window-sash mounted therein, rods extending through the side members of the sash, counterbalancing devices attached to the upper portions of said rods, the lower ends of the rods being roughened and a fusible head secured to the 95 roughened portions of the rods and bearing against the under side of the sash, substantially as described.

In testimony whereof I have signed my name to this specification in the presence of 105 two subscribing witnesses.

CHARLES RUPP.
